UNITED STATES PATENT OFFICE.

HENRY L. WALLACE, OF WALLINGFORD, CONNECTICUT, ASSIGNOR TO
R. WALLACE & SONS MFG. CO., OF WALLINGFORD, CONNECTICUT;
A CORPORATION OF CONNECTICUT.

DESIGN FOR A HANDLE FOR SPOONS, FORKS, OR SIMILAR ARTICLES.

SPECIFICATION forming part of Design No. 35,648, dated February 4, 1902.

Application filed April 22, 1901. Serial No. 57,029. Term of patent 7 years.

To all whom it may concern:

Be it known that I, HENRY L. WALLACE, of Wallingford, in the county of New Haven and State of Connecticut, have invented and produced a new Design for a Handle for Spoons, Forks, and Similar Articles; and I do hereby declare the following, when taken in connection with the accompanying drawing and the letters of reference marked thereon, to be a full, clear, and exact description of the same, and which said drawing constitutes part of this specification.

This invention relates to a design for a handle for spoons, forks, and similar articles; and the design consists in the configuration and ornamentation as herein shown and described.

The sides of the handle of the spoon are bordered by a series of scrolls, alternate scrolls being reversed in position from the intermediate ones. Thus the scrolls A at the inner end of the handle bow inwardly, as do the

long scrolls B at the central portion of the handle and the scrolls C near the outer end, while the scrolls D between the scrolls A B, the scrolls E between the scrolls B C, and the scrolls F on opposite sides of the outer end of the handle bow outwardly. Between the outer ends of the scrolls F is a conventionalized tip G. The several scrolls at the sides of the handle give an irregular edge. 30

I claim--

The design for a handle for spoons, forks, and similar articles as herein shown and described.

In testimony whereof I have signed this 35 specification in the presence of two subscribing witnesses.

HENRY L. WALLACE.
